UNITED STATES PATENT OFFICE

102,836

DESIGN FOR A RETICULE

Elmer Hoover McGowen, Los Angeles, Calif.

Application November 11, 1935, Serial No. 59,474

Term of patent 3½ years

To all whom it may concern:

Be it known that I, Elmer Hoover McGowen, a citizen of the United States and residing at Los Angeles, in the county of Los Angeles and State of California, have invented a new, original, and ornamental Design for a Reticule, of which the following is a specification, reference being had to the accompanying drawing forming part thereof, in which:

Fig. 1 is a side elevational view showing substantially one-half the reticule, the detailed illustration of which is continued throughout the sides of the reticule;

Fig. 2 is a bottom plan view of the reticule shown in Fig. 1, the detailed illustration being continued throughout the size of the bottom of the reticule.

The essence of the invention resides in a reticule having a basket-like contour, the side wall of which is of open work diamond mesh bordered at the top and bottom margins with chain stitching having a lace edging on the upper margin and an open pattern border on the lower margin connecting with the margin of a reticulated bottom wall. The mesh of the body of the reticule progressively increases in size from the bottom to the top as shown.

I claim:

The ornamental design for a reticule, as shown and described.

ELMER HOOVER McGOWEN.
